UNITED STATES PATENT OFFICE.

FREDERICK RATCLIFF, OF NEW BEDFORD, MASSACHUSETTS, ASSIGNOR TO
THE PAIRPOINT MANUFACTURING COMPANY, OF SAME PLACE.

DESIGN FOR A COFFIN-PLATE.

SPECIFICATION forming part of Design No. 22,506, dated June 6, 1893.

Application filed March 31, 1893. Serial No. 468,616. Term of patent 7 years.

To all whom it may concern:

Be it known that I, FREDERICK RATCLIFF, a citizen of the United States, residing at New Bedford, in the county of Bristol and State of Massachusetts, have invented and produced a new and original Design for Coffin and other Plates, of which the following is a specification, reference being had to the accompanying drawings, showing the same.

Figure 1 is a plan view, and Fig. 2 a sectional view on line 2—2 of Fig. 1 of a plate embodying my design.

This invention relates to plates for various uses, but especially coffin plates with special

reference to the name plate or to the handle 15 plate, and the design consists in the configuration and ornamentation as shown in the accompanying illustrations. The body α of the plate is surrounded with border portions α' which are curved at the outer edges separated 20 by shell-like scrolls α^2 .

What I claim is—

The design for a coffin or other plate herein shown and described.

FREDERICK RATCLIFF.
